UNITED STATES PATENT OFFICE.

THOMAS M. FERGUSON, OF HATTIESBURG, MISSISSIPPI.

ROLLER-SKATE.

No. 899,963.

Specification of Letters Patent. Patented Sept. 29, 1908.

Application filed November 4, 1907. Serial No. 400,627.

To all whom it may concern:

Be it known that I, THOMAS M. FERGUSON, a citizen of the United States, residing at Hattiesburg, in the county of Perry and State of Mississippi, have invented certain new and useful Improvements in Roller-Skates; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to safety attachments for roller skates particularly designed to be used by beginners who are not familiar with the art of roller skating, and my invention has for its object to provide certain safety devices which will prevent a novice from falling and will therefore enable him to more quickly and readily learn the art of roller skating.

With this object in view my invention consists in the novel arrangement and construction of a brake or drag at the forward and after ends of each skate.

My invention also consists in the arrangement of a strap or brace extending from the toe of the skate to or near the knee of the skater as will be hereinafter fully described.

Referring to the accompanying drawing: Figure 1 is an elevation illustrating the employment of my safety device. Fig. 2 is an elevation of a roller skate constructed in accordance with my invention, having one pair of wheels removed, and Fig. 3 is an end elevation of a roller skate showing safety attachment.

Like numerals of reference indicate the same parts throughout the several figures in which:

1 indicates the roller skates which may be of any desired style or construction, either four wheel skates or two wheel skates. 2 indicates the usual rollers and 3 the running gear therefor.

A metallic strap 4 carrying a yoke 5 which accommodates a piece of rubber or like material 6 is arranged as shown in the drawing, and 7 is a bolt passing through said rubber or other material 6 for the purpose of securely holding the same in position within the yoke 5. The strap 4 extending from the toe portion downwardly and rearwardly to the front running gear lies obliquely or on a

slant as shown in Fig. 2, the lower end of the metallic strap 4 being secured by any suitable means, it being of course obvious that the specific means of attachment must vary according to the particular design and construction of the skate.

At the rear or after end of the skate a similar strap 8 is employed which extends downwardly and has its forward end suitably secured to the running gear of the rear or after rollers:—a yoke 5 and piece of rubber or other material 6 identical with that on the forward strap is employed on the after strap 8, a bolt 7 securing the rubber or other material rigidly within the yoke 5. As shown in Fig. 2 the yokes 5 and rubber or other material 6 is adjustable on the metallic straps 4 and 8 in order to fit the same to the wishes and particular requirements of the skater, it frequently happening that some beginners have a greater tendency to fall backward than forward; while in other instances the reverse is the case. By means of the adjustment of the brake or drag 6 the same can be set to more quickly catch the skater very near the skate on the forward or after wheels which is the position the skater assumes when the skater is falling.

As shown in Fig. 1 a strap or brace 9 is provided which passes from the forward or toe portion of the skate to a garter strap 10 secured around the leg of the skater at or near the knee. This strap 9 can be tightened or loosened in such manner that when the skater is falling backward the strap 9 will more quickly raise the forward wheels from the floor, thus insuring a quick and sudden engagement of the rear or after brake 5 with the floor thus stopping the forward motion of the skate and preventing a fall.

When the beginner has sufficient self confidence the strap 9 can be removed and the brakes 6 thereafter relied upon to prevent falling. The construction of the safety brake apparatus, however, makes this arrangement particularly desirable to be used by persons versed in the art of skating, for the reason that it at all times enables the skater to make a quick stop without scarring or marring the floor or surface upon which he is skating.

Having thus fully described my invention what I claim as new and desire to secure by Letters Patent of the United States is:—

1. A safety device for roller skates comprising a metallic strap extending from the

forward or toe portion of the skate downwardly and rearwardly to the running gear of the front wheels in such manner that said metallic strap lies obliquely or slantingly 5 from the toe portion, a like metallic strap extending from the heel or after portion of the skate downwardly and forwardly to the running gear of the rear or after wheels in such manner that said last mentioned metallic 10 strap lies obliquely or slantingly from the said heel or after portion of the skate, a yoke on each of said metallic straps and a brake piece of suitable material carried in each of said yokes, each of said yokes being adjustable 15 on its strap in such manner that each of said yokes can be moved to increase or diminish the distance between the skate wheels and the brake piece carried by the yokes, which movement or adjustment of the yokes 20 raises or lowers the said brake piece relatively to the bottom of the wheels, substantially as described.

2. A safety device for roller skates comprising a metallic strap extending from the 25 forward or toe portion of the skate downwardly and rearwardly to the running gear of the front wheels, a yoke on said metallic strap, brake piece carried on said yoke, said yoke being adjustable on said strap in an oblique or slanting direction from the front 30 wheels of the skate in such manner that the distance between the front wheels and the brake piece carried in the said yoke can be increased or diminished and the said brake 35 piece raised or lowered relatively to the bottom of the front wheels, substantially as described.

3. A safety device for roller skates comprising a metallic strap extending from the 40 heel or after portion of the skate downwardly and forwardly to the running gear of the rear or after wheels in such manner that said strap lies obliquely or slantingly from the said heel or after portion of the skate, a yoke 45 carried on said strap, a brake piece of suitable material carried in said yoke, said yoke being adjustable on said strap to increase or diminish the distance between the rear wheels and the said brake piece of suitable material 50 and raised or lowered relatively to the bottom of the rear wheel, substantially as described.

4. A safety device for roller skates com-

prising a metallic strap extending from the forward or toe portion of the skate downwardly and rearwardly to the running gear of the front wheels and secured thereto in such manner that said metallic strap lies obliquely or slantingly from the toe portion of the skate, a similar strap extending from the heel or after portion of the skate downwardly and rearwardly to the running gear of the rear or after wheels and secured to said running gear in such manner that said metallic strap lies obliquely or slantingly 60 from the heel or after portion of the skate, a brake piece of suitable material carried on the oblique or slanting strap at the forward portion of the skate and a similar brake piece of suitable material carried on the 65 oblique or slanting strap at the rear or heel portion of the skate, substantially as described.

5. A safety device for roller skates comprising a brake piece of suitable material 75 mounted at each end of the skate and beyond the forward and after wheels thereof, and a strap or brace passing from the forward or toe portion of the skate adapted to be fastened to the knee of the skater, substantially as described.

6. A safety device for roller skates comprising a brake piece of suitable material mounted behind the rear or after running gear of the skate and above the floor when 85 the skate is in its normal position, and a strap or brace adapted to extend from the forward or toe portion of the skate to a point on the leg of the skater, substantially as described and for the purposes set forth. 90

7. A safety device for roller skates, comprising a metallic strap extending down from one end of the body of the skate in an oblique or slanting direction to one of the running gears of said skate to which running gear said strap is secured at its lower end, and a brake piece of suitable material carried on said metallic strap, substantially as described.

In testimony whereof, I affix my signature, in presence of two witnesses:

THOS. M. FERGUSON.
